Flossmoor, Ill.

Application September 25, 1947, Serial No. 776,030

4 Claims. (Cl. 240—6.45)

1

This invention relates to a battery-operated light adapted primarily for lighting the interior of a purse or handbag or the like.

The principal object of the invention is to provide a light which may be removably attached in the interior of a handbag in a position readily to be actuated when the bag is opened to direct light into the interior to reveal the contents.

The invention contemplates a flash light adapted to be secured in the lining of a handbag or the like, and having a lens or bulb for directing light into the interior of the bag and provided with a readily actuated switch for turning the light on when the bag is opened, and which is automatically extinguished when the bag is closed.

An important object of the invention is realized in the provision of attaching means for removably securing a flash light in the interior of a handbag and which incorporates means cooperating with the body of the flash light to switch the light on and off in accordance with the needs of the operator.

More specific objects of the invention include the provision of attaching means for a flash light having hinged connection therewith and on-and-off switch contacts engageable between the flash light and attaching member, and having spring devices for normally urging the contacts apart.

The foregoing and other and more specific objects of the invention are attained by the mechanism and arrangement illustrated in the accompanying drawings, in which

Fig. 1 is a general front elevation of the flash light of this invention showing the full length of the battery casing;

Fig. 2 is a general end elevational view of the flash light;

Fig. 3 also is a general elevational view of the lower side of the light;

Fig. 4 also is a general end elevational view of the flash light similar to Fig. 2, but illustrating the light actuated to operative position;

Fig. 5 is a general view of a handbag in open position, and showing the application of the flash light therein; and

Fig. 6 is a diagrammatic illustration of the operation of the flash light as applied in a handbag.

The present invention is intended to provide a convenient means of electrically lighting a handbag or the like to obviate the necessity of groping for articles contained therein when it is not otherwise possible to see the contents, and which

2

is readily applicable and detachable for use with and transfer between a plurality of bags, and adapted to be actuated easily to light up the bag in which it is secured and automatically extinguished when released and the bag is closed.

In the drawings, 10 represents a flash light adapted for suspension in a handbag or the like, and comprising a body portion or casing 11 adapted to receive and contain a single dry cell type of battery and having a removable end cap 12 which may be secured in place, if desired, to retain the battery in position after insertion thereof through the open end of the casing. The head portion 13 of the casing, which is shown as integral therewith, is adapted to receive a bulb 14 which may be threaded into the head for purposes of removal and renewability. The head portion is so arranged and disposed as to receive the bulb 14 in a manner to direct the light rays emanating therefrom in a general direction substantially at right angles to the axis of the battery and casing 11.

The flash light is adapted for suspension from a supporting surface to which it may be removably attached by means of hinged bracket 18. The body casing 11 is provided with a generally laterally and upwardly extending lug 16 which is disposed substantially at the center of balance of the flash light as a whole when equipped complete for use including battery and bulb. This lug projects between a pair of complementary spaced lugs 17 on the bracket member 18, and a fixed hinge pin 19 is secured through the assembly to provide a pivotal support for the light.

A compression spring 20 is operatively disposed between the mounting bracket and the casing or lug 16 in position to exert pressure in a direction to cause the flash light normally to swing outwardly, away from the bracket, and this outward movement is limited by means of a limit stop 21 formed integrally with the supporting lug, as best shown in Figs. 2 and 4. The extremity 21 of the lug 16, projecting beyond the hinge point 19, is so formed as to engage the surface of bracket 18 and thereby fix the limit of outward hinging movement of the flash light with the direction of light projection, as represented by the head 13 disposed substantially vertically. The spring 20 is illustrated as comprising a compression type coil spring, and may be retained in operative position between the parts by means of oppositely extending stud members projecting into respectively opposite ends of the spring from the bracket 18 and from the surface on the lug 16 engaged by the spring.

The outwardly spaced condition of the flash light as shown in Fig. 2 represents the off position of the light, but when the casing 11 is moved to the position shown in Fig. 2 in engagement with the bracket 18, the electrical circuit from the battery is completed to the bulb 14, thereby causing it to light, and whereby this might be termed the operative position of the flash light. Contacts 22 and 23 are provided on the battery casing 11 in spaced apart relation, and a single bridging contact 24 is provided on the bracket 18. The contact on the bulb 14 is directly connected with the battery terminal at the front end thereof, while the rim of the socket containing the bulb is connected with the forward contact 23 on the casing 11 and the rear of the battery is connected with the rear contact 22, all by means of metal electrical circuits (not shown) and thus, when the contacts 22 and 23 are pressed into engagement with the contact 24, bridging the space therebetween and serving as an on-and-off switch, the electrical circuit is completed from the battery to light the bulb.

A fastening 25 is incorporated as an integrated part of the supporting bracket at the upper margin thereof and is such that the assembly may be removably secured to the supporting surface.

The flash light assembly as shown is ideally suited for application to a handbag and for use interchangeably between a number of such bags, and as best shown in Figs. 5 and 6, provides a light readily adapted to such use and conveniently actuated for normal operation. As seen in Fig. 5, the light is secured to the lining 26 of a handbag 27 in a position to direct the light rays therefrom into the bag and substantially over the entire contents thereof, and such that it may be conveniently grasped for operation in the same act of supporting the open bag in one hand while searching the contents with the other hand. As indicated in Fig. 6, the mere act of grasping the upper part of the bag and the flash light is sufficient to close the switch, comprised of contacts 22, 23 and 24, and thus energize the light. When the flash light is released, the light goes out automatically with the separation of the contacts whereby to preclude any possibility of the light being left on while the bag is closed and thus prevents accidental discharge of the battery, and assures operativeness of the light for the full life of the battery.

What is claimed is:

1. A switch arrangement for a purse light comprising an attaching bracket associated with the light and including means comprising the sole support of said light in a purse or the like, said light including a casing containing a battery and having a light bulb connected with the battery, an electrical contact on said bracket normally independent of any engagement with the casing, and a pair of spaced electrical contacts exposed on said casing in opposed relation to said contact on the bracket and completing the circuit from said battery to the light bulb upon operative engagement of all of the contacts.

5 2. A purse light including a battery casing containing a battery and having a light bulb connected with the battery, electrical contact members exposed on said casing in spaced apart relation, an attaching bracket associated with said casing and including means comprising the sole support of said light in a purse or the like, said casing being movable relatively toward and away from said bracket and normally having a space 10 therebetween, and electrical contact means exposed on said bracket in opposed relation to said contacts on the casing operatively bridging said contacts on the casing to close the circuit from the battery to said light bulb when the casing is moved toward said bracket to close said space therebetween.

15 3. A purse light including a body assembly including a battery, a light bulb and spaced apart contact members in circuit with the bulb and battery, said contact members being exposed on said body assembly, and a separate relatively immovable electrical contact bridging said members, said body assembly being bodily movable toward said separate contact to effect said bridging of the spaced contact members.

20 4. In an illuminating device for a handbag or the like comprising a battery operated flashlight including a battery casing containing a battery and having a light bulb connected with the battery, a normally open switch device controlling the circuit between said battery and the bulb including a bracket, said casing being hingedly connected with the bracket and said bracket including means comprising the sole 25 support of said illuminating device in the handbag, electrical contact means completing the circuit between said battery and the bulb comprising spaced apart contact members exposed on said casing in opposing relation to said bracket and bridging contact means on the bracket operatively closing the circuit across said contact members, and spring means operative between said bracket and the casing normally maintaining said contact members and bridging contact means in spaced relation.
